[57] CLAIM

The ornamental design for a chair, as shown and described.

DESCRIPTION

FIG. 1 is a front perspective view of a chair showing
my design;

FIG. 2 is a rear perspective view;

FIG. 3 is a rear elevational view; and

FIG. 4 is a side perspective view thereof.

The side of the chair not shown is a mirror image of the side shown in FIG. 4.

FIG. 3

FIG. 4
